DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

4 Sheets Drawing. 27 Pages Specification

An improved program method is shown for determining the similarity of two character strings where they are not necessarily equal character by character. Each character of one character string is compared with each character of the other character string, and the results are stored in a matrix. Each row of the matrix corresponds to a respective one of the characters of the first string, and each column of the matrix corresponds to a respective character of the other string. A logical one value is stored in each matrix position where corresponding characters of the first and second string are equal, and a logical zero is stored in each position where they are not equal. In the event that there is more than one logical one in each row (or in each column, or both), all of the logical ones in that row (or column, or both) except that which is closest to the major diagonal of the matrix are changed to logical zero. In the event that two logical ones in a row (or column, or both) are equidistant from the major diagonal, both may be retained. The remaining logical ones in the matrix are then considered as points on an X, Y coordinate system, and the standard correlation coefficient (which measures linear dependence) of the points is calculated to determine the degree of similarity between the two character strings. A decision that sufficient similarity exists to make a determination that a match has occurred may be based upon various known tests, for example, exceeding predetermined thresholds; or, in the event that a match is made against several character strings, the highest coefficient calculated can be determined as the match. The improved method can be used

in programming areas such as inquiry (or query) systems and the job control language processor of an operating

ing system. The program usually handles missing characters, transposed characters and other common errors. The program can be either a fixed or an adaptive type.

2	---	•			
3	---	---	•		
4	---	---	---	•	

FIG. 2a

FIG. 2b

FIG. 2c

FIG. 1

STEP 1

FORM A MATRIX, M, BY LETTING $M(i;j)$
(WHERE I INDICATES THE ROW AND J INDICATES
THE COLUMN) BE A 1 IF, AND ONLY IF, $A(i)=B(j)$
OTHERWISE, LET $M(i;j)=0$.

STEP 2

IF A ROW OF M CONTAINS MORE THAN ONE 1,
THEN RETAIN ONLY THE ONE CLOSEST TO THE
MAIN DIAGONAL (THE MAIN DIAGONAL IS $M(1;1)$,
 $M(2,2), \dots$)

STEP 3

IF A COLUMN OF M CONTAINS MORE THAN ONE 1,
THEN RETAIN ONLY THE ONE CLOSEST TO THE
MAIN DIAGONAL (THE MAIN DIAGONAL IS $M(1;1)$,
 $M(2,2), \dots$)

STEP 4

CONSIDER THE 1'S IN M AS POINTS ON AN X-Y
COORDINATE SYSTEM. THAT IS, IF $M(i;j)$ IS 1
THEN WE HAVE A POINT WITH THE Y-COORDINATE
EQUAL TO I AND THE X COORDINATE EQUAL TO J.

STEP 5

DETERMINE THE DEGREE OF SIMILARITY BY COMPUTING
THE STANDARD CORRELATION COEFFICIENT (WHICH
MEASURES LINEAR DEPENDENCY OF THE POINTS).
